D. B. McCULLOUGH.
AUTOMATIC QUICK ACTING VISE.
APPLICATION FILED MAY 7, 1917.

Patented Aug. 14, 1917.

UNITED STATES PATENT OFFICE.

DANIEL B. McCULLOUGH, OF DIKE, TEXAS.

AUTOMATIC QUICK-ACTING VISE.

1,237,071.

Specification of Letters Patent.

Patented Aug. 14, 1917.

Application filed May 7, 1917. Serial No. 166,978.

To all whom it may concern:

Be it known that DANIEL B. McCULLOUGH, a citizen of the United States, residing at Dike, in the county of Hopkins 5 and State of Texas, has invented certain new and useful Improvements in Automatic Quick-Acting Vises, of which the following is a specification, reference being had to the accompanying drawings.

10 This invention relates to vises, and the general object of the invention is to provide a very simple and easily operated vise, in which the jaws are automatically held closed upon the work until released.

15 A further object is to provide a vise which is very quick in its action and in which strong pressure may be secured upon the article being held.

20 A further object is to improve the details of construction of vises of this character and to provide a device which is very simple in construction, which may be very cheaply made and which is thoroughly efficient.

25 My invention is illustrated in the accompanying drawings, wherein:

Figure 1 is a side elevation of my improved vise in applied position;

30 Fig. 2 is a side elevation of the vise showing the jaws closed, some of the parts being in section;

Fig. 3 is a front elevation of the vise; and

35 Fig. 4 is a perspective view of the lever for operating the vise.

Fig. 5 is a section on the line 5—5 of Fig. 1.

Referring to these figures, 10 designates the stationary body of the vise, which is in 40 the form of a vertically extending bar provided at its upper end with a jaw 11, the upper extremity of the jaw being rounded, the inner face of the jaw being flat and said inner face being reinforced by the plate 12.

45 Mounted upon the body 10 at any desired height is the collar 13, which is bolted or otherwise attached to the bar 10 in a solid and rigid manner, the two ends of this collar or strap 13 being twisted into a plane 50 at right angles to the plane of the strap or collar and then divergently extended to form bracket arms 14 by which the vise

may be supported upon the work bench or table.

Embracing the upwardly extending bar 55 10 is a metallic strap 15 having rearwardly extending arms or ears 16. This metallic strap or collar 15 is riveted, bolted or otherwise firmly and rigidly attached to the member 10, and between the ears 16 is pivoted the movable jaw 17, which extends upward so that its upper end is level with the upper end of the member 10, the upper end of the movable jaw having a metallic plate 18 attached to its inner face and confronting the plate 12. Attached to the member 10, above the supporting collar 13, are the outwardly projecting arms 19 and pivoted upon the bolt 20, extending through the extremities of the arms, is a lever 21, 60 65 whose inner end is bifurcated or forked as at 22 and angularly deflected, this lever being pivoted upon the bolt 20 approximately at the intersection of its angular extremity with the body of the lever. Disposed between the forked ends of the angular extremity is a roller 23. The outer face of the movable jaw 17 is recessed as at 24, the inner face of this recess having a wear plate 25. If the jaw 17 is of wood, the roller 23 70 75 80 bears against this wear plate. It will be obvious now that upon a depression of the lever 21, the extremity of the angular end 22 will move inward forcing inward the jaw 17. A spring 26, which is mounted 85 upon the member 10, bears against the jaw 17 and urges this jaw outward. This spring 26 is preferably a relatively strong leaf spring. It will be noted that the upper end of the recess 24 is slightly outwardly beveled 90 or inclined and thus when the lever 21 is brought to an approximately vertical position, the angular end 22 of the lever will extend horizontally inward and the jaws will be almost closed. When, however, the 95 lever 21 is forced still farther inward toward the jaw 17, the roller 23 will ride up on this inclined face and force the jaws completely together. It will be seen that the last portion of the movement of the jaw 100 17 is relatively slight and that a great wedging or camming force is exerted by the roller as it moves upward along the face of the recess and as it moves over the inclined

upper end of the recess. Pivotedly mounted upon the extremity of the arm 21 is a locking rod 27, which is arcuate in form and extends downward from the extremity of the lever 21 and through a slot 28 formed in the standard or body 10. This slot 28 is sufficiently large to permit the locking rod 27 to move freely. The extremity of the locking rod is over turned to form a stop 29. 5 For the purpose of engaging the locking rod and holding the jaws closed upon the work, I form the locking rod 27 with a plurality of ratchet teeth 30 and provide a transverse slot 31 extending through the member 10 and provide a spring detent composed of a flat spring 32 attached to the side face of the member 10 and angularly bent and extending inward through the slot 31, the resilience of the spring causing the 15 angular end to be urged upward and against the notches or ratchet teeth 30. The angular end 33 extends out through the slot 31 a sufficient distance so that the foot of the operator may be placed upon the angular end of the spring and the detent 33 forced 20 downward to thereby release the locking rod 27 to permit the jaws to open. Preferably I provide a spring 34 attached to the jaw 17 at its base or lower end which, 25 when the lever 21 is brought to a vertical position or a position contiguous to the jaw 17, will contact with the lever and act to urge it outward as soon as the locking rod 27 has been released. This is necessary inasmuch as the lever, when in a locking position, is practically locked against outward 30 movement by the angular end 22 of the lever being disposed in a horizontal plane or at an inclination to a horizontal plane 35 and beyond its center.

The operation of my invention will be obvious from what has gone before. When it is desired to grasp an article in the vise, the lever 21 is forced downward, closing the jaws upon the work. The locking bar 27 automatically locks the lever in its closed position. When the work has been done, the operator forces downward the detent 33 releasing the locking-rod 27 and the device 45 will automatically open by reason of the springs 34 and 26. It will be seen that the device is very simply made, that it may be readily repaired if it gets out of order, and that a very strong gripping action is secured 50 by reason of the peculiar form of the end of the lever 21 and the peculiar form of the recess 24 within which the roller 23 operates. Furthermore it will be seen that the locking feature does away with the necessity of using the screw in order to force the jaws toward or from each other and that the device has a much quicker action than an ordinary screw vise and also has a very 55 large range of movement.

While I have illustrated the preferable form of my invention, it will be understood that many modifications may be made without departing from the spirit of the invention.

Preferably one of the arms 19, as illustrated in Fig. 1, is formed with an opening 35 and carried by the jaws 11 and 17 are bolt-cutting blades 36 and thus it will be seen that when the jaws 11 and 17 are forced toward each other, the bolt cutting blade 70 which is mounted upon the jaw 17 will pass the opening 35 and coact with the other bolt-cutting blade to cut pieces of iron inserted through said opening 35. Thus whenever the blacksmith desires to cut a 80 bolt or a small rod he can cut it in his vise.

Having described my invention, what I claim is:—

1. In a vise of the character described, a fixed jaw, a movable jaw, a lever operatively engaging the movable jaw to shift it toward or from the fixed jaw, an arcuate locking rod pivoted to the extremity of the lever and having ratchet teeth, and a detent 90 engageable with the ratchet teeth to hold the lever in adjusted position, said detent being shiftable out of the way to release said locking rod.

2. In a vise of the character described, a standard formed at its upper end to provide a fixed jaw, brackets extending outward from the standard, a jaw pivoted at its lower end upon said brackets, ears attached to the standard and extending out upon 100 each side of the movable jaw, a lever having an angular end pivoted between said ears adjacent to its angular extremity, the angular extremity operating against the face of the pivoted jaw to urge the pivoted jaw inward when the lever is shifted downward, an arcuate locking rod pivoted to the extremity of the lever and extending through a slot in the standard and having ratchet teeth, and a spring detent operatively engageable with the teeth of the locking rod to hold the locking rod in adjusted positions, said detent projecting out beyond the standard to afford a pedal whereby the detent may be depressed out of engagement 110 with the locking rod.

3. In a vise of the character described, a standard terminating at its upper end in a fixed jaw, a movable jaw operatively pivoted upon the standard, ears attached to the standard and between which the movable jaw moves, a lever having an angular relatively short end operating against the face of the movable jaw, an arcuate locking rod attached to the lever and passing through a slot in the standard, a detent engageable with the locking rod to hold it in its adjusted positions, a spring urging said 125

jaws apart, and a spring mounted upon the base of the movable jaw and adapted to engage with said lever when the same is shifted to a position to close the jaws, said last named spring urging the lever and locking rod outward when the detent is released.

In testimony whereof I hereunto affix my signature in the presence of two witnesses.

DANIEL B. McCULLOUGH.
